G. I. GOLDWYN

FOLDING COT

Filed Aug. 29, 1925

by *George I. Goldwyn*
Attorneys

UNITED STATES PATENT OFFICE.

GEORGE I. GOLDWYN, OF CHICAGO, ILLINOIS.

FOLDING COT.

Application filed August 29, 1925. Serial No. 53,230.

This invention relates to improvements in folding cots and consists in the matters hereinafter described and more particularly pointed out in the appended claim.

5 One of the objects of the present invention is to provide an improved means for locking the cot in its open position ready for use so that the cot may be shifted or carried about when in said open position without danger 10 of it folding up due to the lifting up on the side rails thereof.

A further object of the invention is to provide an improved fabric or top for the cot which prevents the passage of cold air 15 therethrough and includes cushioning parts along the side rails to prevent the engagement of the limbs of the occupant upon said side rails.

The above mentioned objects of the invention, together with others as well as the many advantages thereof will more fully appear as I proceed with my specification.

In the drawings:—

Fig. 1 is a perspective view of a folding 20 cot embodying my invention as it appears when in its open or unfolded position ready for use.

Fig. 2 is a view in front elevation on an enlarged scale of the pivotal connection between the leg members of one of a pair of legs forming a part of my improved cot construction.

Fig. 3 is a horizontal detail sectional view as taken on the line 3—3 of Fig. 2.

35 Fig. 4 is a detail sectional view through one of the side rails and associated margin of the fabric top of the cot on a further enlarged scale, the plane of the section being indicated by the line 4—4 of Fig. 1.

40 Fig. 5 is a perspective view on an enlarged scale of one of the bracket plates embodied in the pivotal connection between the leg members of one of a pair of legs embodied in the cot.

45 Fig. 6 is a perspective view of a latch member on an enlarged scale secured to one of the leg members and adapted to engage the other leg members in a manner locking them in their open or extended position.

50 Referring now in detail to that embodiment of the invention illustrated in the accompanying drawings:—My improved cot comprises folding side rails 1—1, and foldable X shaped end and intermediate legs 2—2 and 3 respectively, all made of a stand-

ard light weight tubular stock, and a fabric top 4 operatively connected to and enclosing said side rails 1—1.

The side bars or rails each comprises two sections 1^a—1^a which when the cot is in its open extended position meet or substantially abut at their inner ends in the plane of the intermediate legs 3 and engage the top ends of said legs which provide stops for said meeting ends of said side bar sections. Said abutting ends of each pair of side rail sections are connected to said intermediate leg 3 by means of T shaped brackets 5 as best shown in Fig. 1.

The fabric top 4 is preferably made of top and bottom fabric members 6 and 7, respectively (see Fig. 4) and a suitable padding may be interposed between said members and quilted or stitched thereto to exclude the cold air which comes through a single thickness top and chills the occupant. The lateral margin 7^a of the bottom fabric member, which is wider than the top fabric member 6, is folded under and stitched to the main body of the fabric as at 8 to provide a longitudinal pocket 9 at each side of the fabric to receive the associated side rails 1—1. The lateral edges of the top fabric 6 are stitched as at 10 to the marginal parts of the bottom fabric 7 to provide a pocket 80 above each rail to receive a cushioning material or padding 11. As the side rails are made of a stock of substantially small diameter in order to save material and cut down weight, they were heretofore quite annoying to the occupant when shifting positions upon the cot. However, with my improved top fabric, said rails are padded along the top as before described so that the annoyance of bumping the hard rails when occupying the cot is eliminated. Both fabrics are cut away in the vicinity of the brackets 5 to permit the folding of the sections 1^a—1^a of the side rails.

As the construction of each pair of cross legs is alike, a detailed description of one pair of legs will suffice for all. The end legs 2—2 like the intermediate legs 3 are each made up of crossed leg members 12 and 13, respectively, the leg member 12 comprising top and bottom offset leg sections 12^a—12^b suitably connected together at their adjacent ends by front and rear connecting plates 14—14 and one of which is shown in perspective in Fig. 5. Each connecting 100 105 110

plate includes a flat mid portion 14^a which is ribbed longitudinally as at 14^b for stiffness, and top and bottom end portions 14^c—14^d which extend parallel with each other but in offset planes, said end portions extending at an angle to said mid portion. Said end portions are both rounded in cross section to embrace portions of the adjacent ends of said leg sections 12^a—12^b and to 10 which they are riveted as at 15 in Fig. 2. In one edge of each end portion 14^c is formed a notch 14^e the purpose of which will appear later. The mid portion of the leg 13 extends between the mid portions of 15 the associated connecting plates 14 and a rivet 16 passing through said leg portion and plate portions provides the pivotal connection between the leg members 12 and 13. The top ends of said leg member are at 20 tached to brackets 17 which in turn are connected to the ends of the side rails 1—1 in a manner permitting a folding movement between said side rails and leg members. Such a connection between the leg members 25 is strong and rigid and the leg parts are so arranged that when the legs are in their open crossed position, the adjacent end of the leg members 12^a—12^b abut or engage with oppositely disposed points on the mid 30 portion of the leg member 13, which points are spaced apart as shown in Fig. 2. Heretofore when the cot was in its open position and an upward lift was imposed on the ends of the side rails as when carrying the cot about, the leg members would fold together about the axis 16, thus permitting the cot to fold longitudinally against the desires of the persons thus moving the cot.

To overcome this objectionable feature I 40 have provided a simple and efficient means which is carried by one leg member and adapted to be moved into engagement with the other to lock said leg members in their open crossed position. As herein shown, 45 said device is in the nature of a bifurcated latch member 17 (see Fig. 6) including spaced side arms 17^a—17^b which are connected together at one end by a bridge 17^b. The other end of said arms embrace opposite side portions of the leg member 13 and are pivotally connected thereto by a 50 rivet 18. When the leg members 12 and 13 are in their open crossed position as shown in full lines in Fig. 2, the latch member 17 may be swung about the rivet 18 to bring 55 the bridge 17^b into engagement with the notches 14^e of the plates 14—14 providing the pivotal connection between the leg members 12 and 13. The said latch is of such 60 length that the leg section 12^a is slightly

“sprung” outwardly to permit the edge of the bridge to clear that portion of the plate end above the notches 14^e so that when said bridge enters said notches it cannot fall out even if the opened cot be reversed in position, top for bottom. The latch not only holds the legs in their open position but keeps the fabric top taut. In case said fabric top stretches laterally through use, I provide a second notch 14^f as shown in Fig. 70 5 with which the bridge 17^b of the latch may be engaged to take up said stretch. To fold said legs together, the leg section is again “sprung” outwardly to permit the release of the bridge plate when the latch 75 is swung about the pivot 18 toward the leg member 13, after which the legs may be relatively folded into the position shown in dotted lines in Fig. 2.

My improved leg locking latch, though simple in construction locks the legs in open crossed position so that the cot is rigidly held in the position ready for use and will not fold longitudinally when picked up by the side rails to be carried or shifted about. 80

The improved fabric top prevents the cold air or chill from passing through from below and also prevents the occupant from bumping the head, arms or legs upon the 90 hard side rails.

While in describing my invention, I have referred to certain details of construction as well as form and arrangement of the parts thereof I do not wish to be limited thereto except as may be pointed out in the 95 appended claim.

I claim as my invention:

A folding cot embodying therein, side rails and crossed leg members operatively connected thereto, one of said members including leg sections, means including spaced plates connecting the adjacent ends of said leg sections together and between which the other leg member is engaged, means providing a pivotal connection between said 100 other leg member and said spaced plates, which plates each have a notch therein, and a latch plate including spaced side arms and a connecting bridge member at one end, the other ends of said side arms embracing a 110 part of said other leg member and being pivoted thereto for a swinging movement to bring said bridge member into engagement with said notches in said spaced plates to hold said cross leg members in their 115 unfolded open position.

In testimony whereof, I have hereunto set my hand, this 25th day of August, 1924.

GEORGE I. GOLDWYN.
